UNITED STATES PATENT OFFICE

LOTHAR R. ZIFFERER, OF COLUMBIA, PENNSYLVANIA

PIPE HANGER

Application filed August 10, 1927. Serial No. 211,908.

This invention relates to a pipe hanger of the type which employs a supporting ring having a pivoted arm with latch means for connecting it to the ring when a pipe is to be locked in place.

More particularly the present invention is directed to the latch means per se which is improved over previous constructions in several respects. It is sturdy, inexpensive, and 10 self-acting and consequently conduces to facility in the installation of a pipe.

Two suggestive embodiments of this invention are set forth in the accompanying drawing in which—

15 Figure 1 is a view partly in section and partly in elevation of the hanger in its entirety;

Fig. 2 is an elevation of one outside edge thereof;

20 Fig. 3 is a detail in section of the same edge looking from the inside;

Fig. 4 which is a detail in side elevation shows a latch of modified construction;

Fig. 5 is a detail in section taken on line

25 5—5 of Fig. 6; and

Fig. 6 is a front elevation of the latch shown in Figs. 4 and 5.

The hanger herein shown by way of illustration may comprise a sleeve A connected 30 with a collar 7 which is formed on a pipe support B which, in its entirety, is in the general form of a ring. The sleeve is threaded for adjustable connection with a bolt or rod C having an overhead mounting by which to 35 sustain the hanger and its load at a desired elevation. Within the hanger may be carried a pipe D which is movable into or out of position through an opening in the support which may be closed by an arm E pivoted 40 thereto at 3 and provided at its free end with latch means the details of which will now be described.

The free end of the arm E terminates in a head 9 having a pair of beveled surfaces 10 45 forming between them a ratchet tooth 11. The proximate hanger portion is provided with a complementary head 12 having a similar ratchet tooth 13 formed between beveled faces 14 which co-operate with the surfaces 50 10 to deflect the head 9 laterally while mov-

ing to the locking position shown. The pivotal connection 8, of course, is sufficiently loose to permit this to be done. When the teeth are in locking engagement, the arm is firmly supported at its free end. In order 55 that the arm may not shift laterally and thereby become released from locking position, I provide a swinging cap F. As shown, this is pivoted at 16 to the hanger adjacent the head 12, and is adapted to swing upwardly 60 to a past center position where it will remain as indicated by the dotted line in Fig. 1. This cap is in the form of a plate 17 having at its free end a lip 18 for convenient manipulation thereof. On opposite sides of the 65 cap are flanges 19 which overlie the two locking heads when the cap is in down position, as indicated in Figs. 1 and 3. Gravity alone will suffice to keep the head in this position so as to prevent the arm from shifting 70 laterally. With the parts so related, the possibility of the arm becoming unlocked is removed, so that a load may be safely carried in the hanger.

A generally similar construction is set 75 forth in Figs. 4 to 6. In this case, I employ a cap F apertured at 20 to receive a nose 21 which is projected from a head 22 at the free end of the arm E. Adjacent the arm end is a beveled surface 23 which acts to lift the 80 cap when the arm is swung to its locking position. This cap may optionally be held in this position with the aid of a spring which may take the form of a wire 24 coiled around the pivot 16, one wire end being rested against the hanger and the other against the cap. In 85 this manner the cap is always assured of remaining in a position which will latch the arm firmly to the hanger.

The two constructions herein suggested as 90 examples are advantageous in that they are self-operating. The mere act of swinging the arm to locking position will in and of itself cause the latch to function.

I claim:

1. In a pipe hanger, the combination of a support in which is included an arm pivoted at one end to the hanger, a fixed latch carried at the free end of the arm, fixed means on the hanger adapted for automatic co-operat- 100

tion with the latch whereby to releasably connect therewith, the latch connection being made or broken by a lateral movement of the arm relative to the hanger, and means movably carried on the hanger adapted by gravity to engage with both the hanger and arm to prevent relative movement therebetween, substantially as described.

2. In a hanger, the combination of a support in which is included an arm pivoted at one end to the hanger, a latch carried at the opposite end of the arm, and stationary means on the hanger for co-operating with the latch whereby the arm may be connected thereto, the latch connection being made or broken by a lateral movement of the arm relative to the hanger, and pivoted restraining means carried by the hanger adapted in one position to engage with the arm to prevent such lateral movement, substantially as described.

3. In a hanger, the combination of a support in which is included an arm pivoted thereto at one end, the opposite arm end being toothed, means carried by the hanger for engaging with the toothed end of the arm when the latter is moved to locking position, the arm being thereby connected releasably to the hanger, and a pivoted gravity-operated means movable to prevent release of the connection between the pivoted arm and hanger, substantially as described.

LOTHAR R. ZIFFERER.
